UNITED STATES PATENT OFFICE.

JOSEPH P. OUERBACKER, OF LOUISVILLE, KENTUCKY, ASSIGNOR TO THE
O. K. STOVE AND RANGE COMPANY, OF SAME PLACE.

DESIGN FOR A FIRE-PLACE FRONT.

SPECIFICATION forming part of Design No. 21,122, dated October 20, 1891.

Application filed September 14, 1891. Serial No. 405,706. Term of patent 3½ years.

To all whom it may concern:

Be it known that I, JOSEPH P. OUERBACKER, of the city of Louisville, county of Jefferson, and State of Kentucky, have invented and 5 produced a new and original Design for Grates, of which the following is a specification, reference being had to the annexed drawings, forming a part thereof.

Figure 1 is a front elevation of my new grate, 10 and Fig. 2 is a side view of the face-plate thereof with the grate-basket removed.

The leading feature of my design consists of the arched hood A, which rises in a continuous line from a point near the top line of 15 the fire-pot and extends from thence in a curved line to a point at the same elevation at the opposite side thereof, while said hood at its lower ends terminates in a slight molding to relieve the abruptness of its blending 20 with the plain panels B, which commence at the lower ends of said hood and extend from thence to a point near the bottom of the face-plate of the grate-front, so that said hood rises from the general plane of the plate only 25 above the line of the fire-grate. Extending from a point near the bottom of the face-plate

at both sides of the fire-grate there is a raised and ornamented bead C, which forms a continuous line along the sides and across the top of the face-plate along the outer edge 30 thereof. Near each upper corner of the face-plate is a raised branch or twig D, provided with foliage somewhat resembling that of the oak, which branch lies between the hood A and bead C, nearly filling the space between 35 them and rising from an otherwise plain border-section surrounding the hood.

What I claim as new is—

The design for a mantel or grate front, substantially as herein shown and described, the 40 same consisting of the central curved hood A, panels B B, and the border, substantially as shown and described.

In testimony whereof I have hereunto signed my name, in the presence of two at- 45 testing witnesses, at Louisville, in the county of Jefferson, in the State of Kentucky, this 1st day of September, 1891.

JOSEPH P. OUERBACKER.
